No. Fletcher of Providence, R. I.

Assigned to

The Fletcher Manufacturing Company

Letters Patent No. 2336. Dated June 12, 1866.

Design for a Trade Mark

The schedule referred to in this letter Patent and making part of the same.

To all whom it may concern:

Be it known that A. Henry Fletcher of the city and
county of Providence in the state of Rhode Island, have
originated and designed a new design for a trade
mark, of which the following is a full, clear and exact
description, reference being had to the accompanying
specimens making part of this specification.

The design is intended for a trade mark to
designate packages of that variety of braid known
by the name in the trade of "crochet braid".

It consists of a label or ticket of convenient size
to be pasted upon the package of which it is
descriptive, having a surrounding border A,
made up of a representation of the crochet braid, which is
distinguished from other varieties from the fact that
it presents the regular wave outline at the edges
represented in the engraving.

The border is arranged so that within the open
space in the centre, the quantity of braid contained
in the package, its number and description and
the manufacturer's name can be inserted.

What I claim as my invention and desire to
secure by Letters Patent, is

The design for a trade mark herein set forth
and shown.
